CLAIM

The ornamental design for a garden hose nozzle holder,
as shown and described.

DESCRIPTION

FIG. 1 is a front elevational view of a garden hose nozzle holder showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The vertical portions of FIGS. 1-4 have been shown
broken-away to indicate indeterminate length.
